Letters Patent No. 2252 Dated January 30 - 1866

Ante-dated Dec. 27 - 1865

Design for a Clock's Stand

The schedule referred to in these Letters Patent and making part of the same

To all whom it may concern:

Be it known that we, J. Smith and H. Brown of Philadelphia
County of Philadelphia, State of Pennsylvania, have invented or produced
a new and original design for a clock stand, termed the "Oriental" and we
do hereby declare the accompanying Drawing with the following explanation
of the same, to form a full clear and exact description of the said Design.

The view in the accompanying drawing represents the Oriental
Clock stand in perspective, A being the top plate; B the side plate; D the bottom
plate; E; the upper front plate; F; the lower front plate; and G; the hearth plate.

The top plate A, is plain, and edged with a plain moulding. The
side plate B, has plain mouldings at each vertical edge, and an ornamental
moulding at the several edges and has a panel H, and two doors I, J, each of
which has a plain moulding on its edges, enclosing the ornamental work shown
in the drawing.

The bottom plate D, is plain and edged with a plain moulding.

To the upper front plate E, are hung two doors similar to those
on the side plate, and near each side of the plate is a panel of the form shown
in the drawing.

The lower front plate F, is plain, with the exception of an ornamental
moulding at the bottom, similar to that on the side plate.

The hearth plate G, is plain, and is edged with an ornamental
moulding.

085. 2252

2

We claim The ornamental figures and forms substantially as shown in and by the accompanying drawing the whole forming an ornamental design for a cash store.

In testimony whereof, we have signed our names to this specification in the presence of the subscribing witnesses.
